LIFTING DEVICE

Jacques M. J. Riboud, Mount Washington, Md., assignor to Specialty Equipment and Machinery Corp., New York, N. Y., a corporation of Maryland

Application March 1, 1944, Serial No. 524,835

1 Claim. (Cl. 254—8)

1

My invention relates to a lifting or elevating device, and while I will describe same in connection with a particular use, i. e., a limber for use with a field gun, my invention may be used equally well for many other purposes, and is to be limited only by the scope of the appended claim.

The average field gun mount usually comprises a wheeled support for the gun, and a trail, the trail being hooked onto the limber during travelling movement. The weight of the gun may often be quite substantial, and poses a problem not only in lifting same and securing it to the limber, but also in unhooking same from the limber and dropping it to the ground when it is desired to locate the gun in firing position.

The main object of my invention, therefore, is the provision of a device for lifting objects from the ground and locking same in elevated position.

Another object of my invention is the provision of a lifting device for use with a moving vehicle, which device is actuated by movement of the vehicle.

Another object of my invention is the provision of a lifting device comprising a shaft, and an angulated lever, one arm of which is secured to the object to be lifted and the other arm is connected to the lifting force, said lever being pivotally mounted on the shaft.

Another object of my invention is the provision of a lifting device which comprises a support and a shaft thereon, a lever pivoted on the shaft, and having a movable connection between the shaft and lever, movement of which connection actuates the lever to raise or lower objects engaged thereby.

Another object of my invention is the provision of a lifting device which comprises a support and a shaft, a lever pivoted on the shaft and having a movable connection between the shaft and the lever, movement of the connection altering the leverage ratio between the lever and the shaft.

Another object of my invention is the provision of a lifting device of a shaft pivoted on a support and a lever pivoted on the shaft, and means on the shaft whereby the leverage ratio between the lever and the shaft may be readily altered.

Another object of my invention is the provision of a lifting device which comprises a wheeled mount, a shaft thereon, a collar secured to a moving vehicle, and a lever for securement to the object to be lifted and to the moving vehicle, the lever being angulated and pivotally mounted on the shaft, and secured to the collar.

Still another object of my invention is the pro-

2

vision of a lifting device which comprises a shaft, a lever pivoted thereonto, and sliding means to actuate the lever whereby to raise objects secured to the lever.

Still another object of my invention is the provision of a lifting device which may be quickly actuated to raise or lower objects to which it may be secured.

Other and further objects of my invention will be obvious from the following description of an illustrative embodiment of my invention, and still others specifically referred to hereinbelow.

In the drawings annexed hereto and forming a part hereof:

Figures 1, 2, 3, 4 are side elevational views showing various stages in the lifting of a field gun using the device of my invention.

Fig. 5 is a side elevational view of one form of device constructed according to and embodying my invention;

Fig. 6 is a top plan view thereof; and

Fig. 7 is a detail of the locking mechanism, partly in section.

Reference number 10 indicates a field gun having a body 12 mounted on wheels 14, 14 at the front, and flat-bottomed, ground-gripping jack legs 16, 16 at the rear. These rear legs 16, 16 must, of course, be raised above the ground before the gun 10 may be shifted readily, on its

wheels 14, 14, from one side to another. A suitable eye-piece or ring 18 is provided at the rear of chassis 12, mounted on a rigid extension-bracket assembly 20, whereby the gun may be engaged by the lifting and travelling mechanism.

It is to be noted that bracket 20 and engaging ring 18 are spaced outwardly from, and in line, with chassis 12. Thus, lifting and moving forces applied to chassis 12 at ring 18 are directly transmitted to the rear end of the chassis through the bracket arms 18.

My lifting device comprises a metal shaft 30 mounted on a pair of wheels 32, 32 and braced by angulated rods or brackets 34, 36. The wheels 32, 32 may be mounted on a conventional axle,

if desired, although I have shown wheels 32, 32 mounted onto stub shaftings 38 to which brackets 34, 36 are secured. If desired, shaft 30 and brackets 34, 36 may be formed, as by casting or otherwise, as one piece. Shaft 30, at the front end thereof and on one side, is provided with a

rack comprising a plurality of forwardly extending teeth 40, 40, and a slidably concentric collar 42 is provided about shaft 30, having an internal catch 44 which is normally spring-46 urged into engagement with teeth 40 to lock collar 42.

Still another object of my invention is the pro-

against rearward movement against the biasing of teeth 40.

The rear end 50 of shaft 30 is split, and angulated lever 60 is pivotally secured within the split end by means of a pin 62, which passes through shaft 30 and the point of angulation of lever 60. Lever 60 is bent into an obtuse angle, the lower reach or arm 64 thereof terminating in a hook member 66, and the upper reach or arm 68 thereof being pivotally secured to the rear end of a link rod 70, the front end of which is connected to collar 42. Thus, as collar 42 is shifted back and forth along shaft 30, lever 60 is pivoted about pin 62 to raise or lower reach 64.

A hollow sleeve 90 is mounted within collar 42, and is screw engaged with a socket 92 at 93. Coil spring 46 is held within sleeve 90 bearing against catch 44. As socket 92 is unscrewed by counter-clockwise rotation thereof, bearing sleeve 90 outwardly, catch 44 is lifted out of engagement with teeth 40, thereby permitting collar 42 to be shifted freely back and forth along shaft 30. A bail or ring 80 is connected to the front of collar 42 so that the collar may be attached to a lorry as L.

Figs. 2 and 3 show gun 10 at rest on the ground. In Fig. 3 my lifting device is shown backed up in proximity to the rear of chassis 12, and shaft 30 pivoted about the wheel axle or stub shafts to permit hook 66 to be threaded through ring 18. Shaft 30 is then brought into horizontal position and ring 80 hooked onto the motive power, as lorry L. It may not be at all necessary to lift shaft 30, as in Fig. 3, for sleeve or collar 42 may be brought as near the rear end of shaft 30 as is possible to thereby swing reach 64 down as low as may be necessary. Socket 92 is then rotated clockwise to force catch 44 onto spring-urged engagement with teeth 40.

As lorry L moves forward, in the direction of the arrow, collar 42 is slid forwardly along shaft 30, catch 44 riding over the angled faces of teeth 40 carrying link 70 along with it and exerting a forward pull on reach 68 of lever 60. Lever 60 is pivoted about pin 62 and causes reach 64 to rise and lift the rear end of chassis 12 along with it. A suitable stop, as 93, is provided at the end of shaft 30 to limit movement of collar 42, and the biasing of teeth 40 and catch 44 prevents the return movement of collar 42 until the socket 92 is released. Figs. 3, 2, 4 and 1 show successive stages in the operation of my device.

As collar 42 is shifted along shaft 30, the distance between hook 66 and the center of rotation of shaft 30 is changed, and the leverage ratio of my device as a lever is thereby altered, since shaft 30 pivots about stubs 38. Thus, for any particular purpose, it is easy to determine the optimum leverage ratio merely by shifting collar 42 back and forth. My device may therefore be manually operated as a lever, having changeable leverage ratios, for any desired purposes. In Figs. 3 and 4, I have illustrated also the manner in which my device may be manually operated to lift an object as chassis 12. In Fig. 3 shaft 30 is pivoted upwardly on its support and hook 66 engaged in ring 18, bringing

the shaft down thereupon causes a lifting of the chassis, as shown in Fig. 4.

When it is desired to drop the rear of chassis 12 onto the ground for firing the gun, the lorry is stopped. Ring 80 may be disengaged completely from the lift. Socket wrench 92 may be actuated to draw catch 44 out of engagement with teeth 40, and lever 60 will pivot about its axis at 62 to permit chassis 12 to drop to the ground. In the alternative, as is possible with my device, catch 92 is released to permit the gun to drop to the ground while still engaged to the lift, and the lift is still engaged to the lorry.

Both the raising and lowering operations are quickly and easily accomplished. My device can be fabricated and assembled easily and quickly and its operation is exceedingly simple.

I have, with my new and improved lifting device, made possible the formation of a combination which in and of itself is new and extremely useful, that is, a combination comprising an object to be lifted partially off the ground and rested on wheel supports, a lifting device engageable with the object to be lifted, and a moving or tractoring device which is engageable with the lifting device, in which combination forward movement of the moving device actuates the lifting device to raise the engaged end of the object to be lifted. As movement of the tractoring device ceases, the lifting device is locked in operative position to continue to support the lifted object off the ground. When key wrench 92 is released, the lifting device permits the lifted object to drop to the ground. Key wrench 92 may be actuated from a remote position, as from the driver's seat on lorry L, the tractoring device, to permit the lifted object to be dropped down to the ground or other resting place.

Having now described my invention, what I claim and desire to secure by Letters Patent is:

A lifting device comprising a shaft and an obtusely angulated lever having two arms and pivotally secured to the end of the shaft at the point of angulation of the lever, a collar on the shaft and slidably therealong, a link connecting the collar and lever, the shaft having a rack, and the collar having means therewithin normally engaging the rack permitting free movement of the collar in the direction along the shaft away from the point of angulation of the lever.
